OLIVER WICKHAM, OF NEWTON, SINGAPORE, STRAITS SETTLEMENTS.

APPARATUS FOR FILLING RECEPTACLES WITH LIQUID.

1,163,494.

Specification of Letters Patent.

Patented Dec. 7, 1915.

Application filed December 30, 1913. Serial No. 809,526.

To all whom it may concern:

Be it known that I, OLIVER WICKHAM, a subject of the King of Great Britain, residing at "Kya Lama," Chancery Lane, 5 Newton, Singapore, Straits Settlements, have invented certain new and useful Improvements in or Relating to Apparatus for Filling Receptacles with Liquid, of which the following is a specification.

10 This invention relates to improvements in apparatus for filling bottles, jars and other receptacles with liquids and has for its object to produce an apparatus which shall be more simple in construction and more reliable in action than those hitherto in use.

15 The essential feature of this invention is the use in such an apparatus of a siphon having a single outlet or long leg and a double inlet or short leg each of said short 20 legs or short leg members communicating with a separate vessel or source of supply.

25 In carrying the invention into effect a reservoir or vessel which is adapted to contain the liquid with which the bottles or other receptacles are to be filled, has connected thereto a siphon having a double inlet or short leg and a single outlet or long leg, one of the short legs or inlet members (hereinafter termed the main short leg) being connected to the reservoir and the other (hereinafter termed the auxiliary short leg) being connected with an auxiliary vessel, means being provided between the main short leg and the reservoir whereby siphonic 30 action may be started or induced in the siphon system. The auxiliary vessel may be supplied from the main reservoir or it may be connected with a separate and independent source of supply, and it may also be provided with means whereby the rate of flow thereinto of the liquid supply may be varied or adjusted. There is also provided means, which may be of well-known type, whereby the level of the liquid in the reservoir is kept 35 constant.

40 In order that the invention may be clearly understood, reference is made to the accompanying drawings, in which:—

Figure 1 is a partly diagrammatic sectional elevation of one form of apparatus made according to this invention, and, Fig. 2 is an elevation of a modified form of apparatus.

45 Referring to the drawings, A indicates a tank or other suitable vessel containing the liquid with which the receptacles are to be

filled, B is a pipe connecting the tank A with the source of supply, the entry of the liquid into the tank A being regulated and the level therein kept constant by means of the float controlled valve device shown. This valve arrangement consists of a valve C connected to a rod D hinged to the valve casing at E, its other end being connected with a float F the stem of which is suitably supported in guides G.

50 Suitably mounted or supported in relation to the reservoir, is a siphon H, which is as shown provided with a single exterior or long leg I and a double interior or short leg comprising a main short leg K and an auxiliary short leg L. The main short leg K is connected to the cylinder M of a single-acting pump, near one end thereof, the cylinder being supported on the floor of the tank. 55 The cylinder M is fitted with a piston N having a valve V of the "flap" type therein as shown, the said piston being adapted to be reciprocated therein by means of a bell crank lever P P' supported on a shaft Q carried in two brackets R, the said bell crank lever P P' being connected to the piston N by a connecting link S, the other end of the bell crank lever being made long enough to project above the level of the liquid and having a 60 handle T by means of which it can be operated as hereinafter described. Means are provided for varying the length of stroke of the piston, and this is accomplished in this instance by providing a stop piece U movable on the shaft Q, a lug being cast thereon which cooperates with a pin or rod U' carried in an extension of the brackets R. One end of a rod W is connected to the stop piece and the other end of the rod W is connected to a screwed piece X through which passes a bolt Y which is fixed in the handle T so that it is free to turn, but restrained from moving in the direction of its axis as shown. The auxiliary short leg L of the siphon dips 65 into an auxiliary vessel Z mounted upon the pump cylinder N, this auxiliary vessel being provided with an aperture J opening into the tank A, the said aperture J being provided with a screw-down valve 2 controlled by a hand-wheel 3 which enables the area of the aperture J to be varied at will. A suitable support 4 is provided beneath the long or outlet leg I of the siphon for the receptacles 5 that are to be filled.

70 In operation, the receptacles 5 are placed on the support 4 and the pump is operated

by means of the handle T being pulled over in the direction of the arrow, the piston N moving to the position N' as shown in dotted lines. Liquid is thereby forced from the 5 reservoir A through the main siphon until the legs I and K are both full of liquid, when siphonic action will commence, the liquid running from the long leg I into the receptacle 5. Directly the siphonic action 10 has commenced in the main siphon I K an additional siphonic or suction action will be induced or set up in the leg I dipping into the auxiliary vessel Z, so that if the rate of ingress of the liquid to the auxiliary vessel Z through the opening J be less 15 than the rate of egress of the liquid through the auxiliary short leg L of the siphon, it will be readily understood that the level of the liquid in the vessel Z will fall, and will 20 continue to fall until it falls below the end of the leg L. When this occurs, air will immediately rush up the auxiliary short leg and break the siphonic action in the main system I K and thus stop further supply 25 of liquid to the receptacle 5. The handle T is then pushed forward again to its initial position, when the cylinder M will fill with liquid through the valve V and the auxiliary vessel Z will also refill. The apparatus is 30 then in the starting position again, and on the handle T being again pulled, the above mentioned cycle of operations will be repeated.

In the modification illustrated in Fig. 2, 35 the valve V is dispensed with, the piston being made solid, and openings 6 formed in the cylinder M at opposite sides thereof for the admission of liquid from the tank A. It will be understood that in some cases one 40 opening 6 may suffice. The leg K is also connected with the cylinder M by the pipe 7 as shown. In this construction, when the apparatus is in the position shown in the drawing, liquid will be admitted through 45 the openings 6 into the cylinder M and completely fill it. When now the lever P' is actuated in the manner before mentioned with reference to Fig. 1, the piston N will move forward, and at the first part of its 50 travel cover the opening or openings 6, and as it moves forward still farther the liquid in front of the piston will be forced through the siphon K I, after which the action of the apparatus will be substantially the same as 55 that described with reference to Fig. 1, with the exception that the siphon K I, which is, in the apparatus as shown in Fig. 1, fed through the valve V in the piston, when the latter is at the end of its stroke, will be now 60 fed through the branch or by-pass pipe 7. It will be understood that this by-pass connection must be inoperative until the siphonic action has started, and for this purpose the piston may be made sufficiently 65 thick to cover the end of the pipe 7 con-

nected with the cylinder M until the siphonic action has commenced. It will be noted that the leg K of the siphon is shown in Fig. 2 connected to the end wall of the cylinder M, which construction may in some 70 cases be preferable to that shown in Fig. 1.

Instead of connecting the auxiliary vessel with the liquid in the reservoir, it may be connected with an independent source of supply, for the admixture of syrup, flavoring or other liquid, where the apparatus is used for filling receptacles with beverages. The auxiliary vessel also, need not be situated inside the main reservoir but may be outside thereof or in any convenient relation thereto.

Where it is required to fill a number of vessels simultaneously, or consecutively, a number of siphons may be provided and adapted to be supplied from the same or independent sources, or the apparatus may be arranged to work in connection with suitable automatic or hand operated means, such as a revolving turntable, traveling bands or the like for feeding the receptacles to the apparatus, these means being, if necessary, connected with the pump mechanism so as to act in synchronism therewith.

I claim:—

1. Apparatus for filling receptacles with liquid comprising in combination, a main reservoir, an auxiliary reservoir, and a siphon having a single long leg and two short legs, one of said short legs being supported within the main reservoir, and the other short leg being supported within the auxiliary reservoir, and pump mechanism comprising a valved piston and cylinder with means for operating the piston, substantially as and for the purpose described. 100

2. Apparatus for filling receptacles with liquid comprising in combination a main reservoir, an auxiliary reservoir situated within the main reservoir, a siphon having a single long leg and two short legs, one of said short legs being supported within the main reservoir and the other short leg being supported within the auxiliary reservoir, and pump mechanism operatively connected with the reservoirs, substantially as 105 and for the purpose described. 110

3. Apparatus for filling receptacles with liquid comprising in combination a main reservoir, an auxiliary reservoir situated within the main reservoir and communicating therewith, a siphon having a single long leg and two short legs, one of said short legs being supported within the main reservoir and the other short leg being supported within the auxiliary reservoir, and pump mechanism operatively connected with the reservoirs, substantially as and for the purpose described. 115 120

4. Apparatus for filling receptacles with liquid comprising in combination, a siphon 130

- having a single long leg and two short legs, two liquid containing vessels, a connection between one short leg and one vessel, a connection between the other short leg and 5 the other vessel, and mechanism operatively connected with one of said short legs for inducing siphonic action in the siphon, substantially as and for the purpose described.
5. Apparatus for filling receptacles with 10 liquid comprising in combination, a siphon having a single long leg and two short legs, two liquid containing vessels, a connection between one short leg and one vessel, a mechanism operatively connected with said short 15 leg and adapted to induce siphonic action in the siphon, a connection between the other short leg and the other vessel, and an adjustable mechanism connected with said other vessel, whereby the rate of flow of 20 liquid therefrom through said siphon may be regulated, substantially as and for the purpose described.
6. Apparatus for filling receptacles with 25 liquid, comprising in combination a main reservoir, an auxiliary reservoir of smaller capacity than the main reservoir, a connection between the main reservoir and the auxiliary reservoir, a siphon having a single long leg and two short legs, a connection 30 between one short leg and the main reservoir, a connection between the other short leg and the auxiliary reservoir, and a mechanism operatively connected with the short leg in the main reservoir and adapted to 35 induce siphonic action in the siphon, substantially as and for the purpose described.
7. Apparatus for filling receptacles with 40 liquid comprising in combination, a main reservoir, an auxiliary reservoir of smaller capacity than the main reservoir and situated within the main reservoir, a connection between the main reservoir and the auxiliary reservoir, a siphon having a single long leg and two short legs, a connection between one 45 short leg and the main reservoir, a connection between the other short leg and the auxiliary reservoir, and a mechanism oper-
- atively connected with the short leg in the main reservoir and adapted to induce siphonic action in the siphon, substantially 50 as and for the purpose described.
8. Apparatus for filling receptacles with liquid comprising in combination, a main vessel, an auxiliary vessel of smaller capacity than the main vessel and situated within 55 said main vessel, a connection between the main vessel and the auxiliary vessel, a siphon having a single long leg and two short legs, a connection between one short leg and the main vessel, a connection between the other short leg and the auxiliary vessel; a mechanism operatively connected with the short leg in the main vessel and adapted to induce siphonic action in the siphon, and an adjustable device connected 60 with the auxiliary vessel and adapted to vary the rate of flow of liquid between the main vessel and the auxiliary vessel, substantially 65 as and for the purpose described.
9. Apparatus for filling receptacles with 70 liquid, comprising in combination, a main reservoir, an auxiliary reservoir of smaller capacity than the main reservoir and situated within the main reservoir, a connection between the main reservoir and the auxiliary 75 reservoir, a feed device for supplying liquid to the main reservoir, float mechanism situated within the main reservoir and operative upon such feed device to maintain the liquid in the reservoirs at a constant level, a siphon 80 having a single long leg and two short legs, a connection between one short leg and the main reservoir, a connection between the other short leg and the auxiliary reservoir, and a mechanism operatively connected with 85 the short leg in the main reservoir and adapted to induce siphonic action in the siphon, substantially as and for the purpose described.
